UNITED STATES PATENT OFFICE.

WILLIAM E. GOLDING, OF WAKEFIELD, NEW YORK.

EXTENSION-GEAR.

SPECIFICATION forming part of Letters Patent No. 593,932, dated November 16, 1897.

Application filed July 28, 1897. Serial No. 646,189. (No model.)

To all whom it may concern:

Be it known that I, WILLIAM E. GOLDING, of Wakefield, county and State of New York, have invented a new and Improved Extension-Gear, of which the following is a full, clear, and exact description.

The object of the invention is to provide a new and improved extension-gear more especially designed for bicycle sprocket-wheels and arranged to permit a convenient and secure attachment of an extension sprocket-wheel on the one used on the machine.

The invention consists principally of a sprocket-wheel rim formed with sprockets and having flanges on both sides engaging opposite faces of the sprocket-wheel on the machine.

The invention also consists of certain parts and details and combinations of the same, as will be fully described hereinafter, and then pointed out in the claims.

Reference is to be had to the accompanying drawings, forming a part of this specification, in which similar characters of reference indicate corresponding parts in all the figures.

Figure 1 is a front face view of the improvement. Fig. 2 is a rear face view of the same. Fig. 3 is a transverse section of the same on the line 3 3 of Fig. 2. Fig. 4 is a perspective view of part of the improvement as applied and previous to forming the flange from one of the bosses on the rear face of the sprocket-wheel, and Fig. 5 is a transverse section of the same on the line 5 5 in Fig. 4.

The sprocket-wheel A on the machine and to be increased in size by the extension-gear is formed with the usual rim A' and the teeth A², as is plainly illustrated in Figs. 1 and 2. The extension-gear is in the form of a circular rim B, formed on its inside with recesses B' to fit laterally over the teeth A² of the sprocket-wheel A, the said rim being also provided with the usual teeth or sprockets B² for engagement by the sprocket-chain.

On one face of the rim B are formed a plurality of flanges B³, each adapted to engage part of the rim A' and the sides of the adjacent teeth A², as is plainly shown in Figs. 1, 3, and 5, to prevent lateral movement of the rim B on the sprocket-wheel A in one direc-

tion. On the opposite face of the rim B, and preferably directly opposite the flanges B³, are formed bosses B⁴, adapted to pass between two adjacent teeth A² of the wheel A when the rim is laterally applied on the sprocket-wheel, and the flanges B³ abut against one face of the said wheel. (See Fig. 5.)

When the rim B has been placed in position on the wheel A, as described, then the bosses B⁴ are hammered or otherwise formed into flanges B⁵, (see Figs. 2 and 3,) corresponding in shape to the flanges B³ and likewise engaging part of the rim and adjacent teeth A² of the sprocket-wheel A, directly opposite the flanges B³. Thus when the bosses B⁴ are hammered into flanges B⁵, as described, the rim B is securely locked or fastened on the sprocket-wheel A and is held against lateral movement in either direction, at the same time bringing the sprockets B² into alinement with the sprockets or teeth A² of the wheel A.

It is expressly understood that the device as manufactured and sold is formed on one face with the flanges B³ and on the opposite sides with only the bosses B⁴, so as to permit of conveniently placing the rim in position on the peripheral surface of the sprocket-wheel A, and when this has been done then the bosses B⁴ are formed into flanges by pressing the same to lock the rim securely in place on the sprocket-wheel, so as to form an extension-gear for the same.

Having thus fully described my invention, I claim as new and desire to secure by Letters Patent—

1. An extension-rim having a plurality of flanges on one face, and a plurality of bosses on the opposite face, the bosses being adapted to be formed into flanges, substantially as shown and described.

2. An extension-rim having a plurality of flanges on one face, and a plurality of bosses on the opposite face, the bosses being adapted to be formed into flanges, the said flanges and bosses being arranged one opposite the other, as set forth.

WILLIAM E. GOLDING.
